J. R. MACLEAR

AWNNG CONTROL MEANS

Filed Oct. 6, 1922

Patented June 26, 1923.

1,460,359

UNITED STATES PATENT OFFICE.

JAMES R. MACLEAR, OF DENVER, COLORADO, ASSIGNOR TO FRANK R. ASHLEY, OF DENVER, COLORADO.

AWNING CONTROL MEANS.

Application filed October 6, 1922. Serial No. 592,924.

To all whom it may concern:

Be it known that I, JAMES R. MACLEAR, a citizen of the United States, and a resident of 482 So. Corona St., Denver, county 5 of Denver, Colo., have invented an Improvement in Awning Control Means, of which the following description, in connection with the accompanying drawings, is a specification, like letters on the drawings 10 representing like parts.

My present invention relates to awnings, and more particularly to an improved controlling and operating mechanism therefor.

Heretofore considerable difficulty has been 15 experienced in operating; that is, raising and lowering awnings, and particularly large awnings as, due to the heavy weight of such awnings, it has been difficult to safely and easily operate the controlling mechanism. Such prior mechanism are so slow 20 operating as to be inefficient, and regardless of the type heretofore used it has been seemingly impossible to devise a locking mechanism that will efficiently lock the operating 25 mechanism, and therefore the awning, in any desired position, while yet capable of being readily unlocked and locked. Further, prior types of operating mechanism 30 have been operable only from the outside 35 of a building or other structure on which the awning is located although it is extremely desirable that such mechanism be operative from the inside of a building, it being understood, of course, that the operating mechanism proper be situated on the outside of the building to avoid complexity of construction.

In my present invention I have obviated the objections of prior apparatus of this 40 type and have designed a structure that may be operated equally well from the outside and the inside of a building or other structure and in which the mechanism may be locked securely in any desired position 45 and readily unlocked when it is desired to change the position of the awning and also a structure in which the operating crank, which is the usual means of operating such structure, may be removed from the device 50 to prevent tampering with the device by unauthorized persons.

The principal object of my invention is 55 an improved awning operating device adapted particularly for operating heavy awnings.

Another object of my invention is an improved operating device adapted to be located on the outside of a building and operable either from the inside or outside of a building.

Other objects and novel features of the construction and arrangement of parts comprising the same will be apparent as the description of the invention progresses.

In the accompanying drawings illustrating the preferred embodiment of my invention—

Fig. 1 is a side elevation of an awning and the operating mechanism therefor;

Fig. 2 is a front elevation of the operating mechanism, and

Fig. 3 is a vertical sectional elevation on the line 3—3 of Fig. 2.

Referring to the drawings, 10 designates a side wall of a building such, for instance, as that portion of a wall adjacent to a large door or store window, and on the outside of such building is secured a member 11 to which is pivotally attached a frame 12 on which is mounted an awning 13, the upper edge of this awning being secured to the wall 10 on the line 14 in any convenient manner. Secured to the front end of the frame 12 at the point 15 are operating cords 16, it being assumed that the awning 13 is of such size and weight as to require a plurality of operating cords, and these cords pass over a pulley or pulleys 17 secured to the wall 10 adjacent the line 14 and pass downwardly through a guideway 18 also secured to such wall 10, and the ends of such operating cords 16 are secured to a drum 19. This drum 19 is securely fastened on a shaft 20 rotatably mounted in back and front plates 21 and 22 respectively, of an enclosing box, the box being provided with a bottom plate 23. In the preferred form of my invention the back and front plates 21 and 22 and the bottom plate 23 are cast integral with each other to form a housing for the drum 19, as above noted. This box is provided with a cover 24 secured to the box in any suitable manner, and is provided with an elongated slot 25 to allow lateral movement of the cords 16 as such

100 cords are laid onto, and paid off from, the drum 19, as clearly indicated in Fig. 3. Secured on the shaft 20 is a wide faced spur gear 26 which meshes with, and is driven by, a relatively narrow faced spur gear 27 110

that is secured to, and rotatable with, a shaft 28 that is rotatably mounted in suitable bearings in the back and front plates 21 and 22 respectively. Preferably this shaft 28 is mounted in the position shown in Fig. 3; that is, beneath the drum 19 and gear 26, but it is within the scope of my invention to mount such shaft above such drum 19 and gear 26 or in any other position in the housing relative thereto. In addition to being rotatably mounted in the back and front plates 21 and 22 respectively, such shaft 28 is also slidably mounted within bearings, and on this shaft 28 is secured by set screw 29 a collar 30, and between the collar 30 and the inner face of the back plate 21 is a compression spring 31 which tends to force the shaft 28 to the left, as viewed in Fig. 3. Secured to the face of the spur gear 27 on the face adjacent the inner face of the front plate 22 is a pin 32 which is adapted to engage in any one of a plurality of holes 33 arranged in a circle around the shaft 28 so that, when the shaft 28 is forced to the left, as viewed in Fig. 3, by the compression spring 31, the pin 32, engaging with one or the other of holes or perforations 33, locks such shaft 28, and therefore the drum 19, against rotation. The left hand end of the shaft 28 is provided with a non-circular hole in which fits the corresponding non-circular end of a crank handle 34 which is utilized to rotate the shaft 28.

The operation of my improved device is as follows, it being assumed that the awning 13 is in the position shown in Fig. 1 and that it is desired to furl such awning or raise the outer end thereof into such a position that the frame 12 will extend substantially forwardly to the wall 10. The operator will insert the non-circular end of the crank 34 into the non-circular hole of the shaft 28 by pressing on such crank, will compress the spring 31 and move the pin 32 out from engagement with the hole or perforation 33 in which it was located. The shaft 28 may now be rotated, pressure being exerted against the tension of the spring 31 to keep the pin 32 out of engagement with the holes 33, and the spur gear 27 engages with the gear 26, and rotates the shaft 20, and therefore the drum 19, to wind up the cord 16 onto such drum, thereby raising the outer end of the awning and movement continuing will bring the frame 12 into substantial parallelism with the wall 10. After the awning 13 is in the desired position, pressure on the shaft 28 is removed whereupon the spring 31 will force the shaft 28 to

the left, as viewed in Fig. 3, and the pin 32 will be forced in one or the other of the holes 33 thereby locking the awning in the position to which it has been moved. By reversing the above operation, the awning may be moved from the position into which it has been moved and locked into the position shown in Fig. 1, or into any intermediate position.

While the invention has been shown as applied to an outside drive mechanism, it is to be understood that I may extend the shaft 28 through the wall 10, reversing the positions of the gears 27 and 26 and the drum 19 on their respective shafts and that the device when so located will operate equally well with the position in which it has been shown and described.

Having thus described my invention, what I claim as new is:

1. An improved awning operating mechanism comprising a rotatable shaft, a drum secured thereto and to which the awning operating cords are attached, a gear secured to said shaft, a second shaft mounted parallel to, and slidably longitudinally with respect to, said first shaft, a gear secured to said second shaft and engaging with the first gear to rotate the drum, locking means including a pin secured to the gear on said second shaft and movable into and out of locking position by the longitudinal movement of said second shaft.

2. An improved awning operating mechanism comprising a housing, a shaft rotatably mounted therein, a winding drum and a wide faced gear secured to, and rotatable with, said shaft, a second shaft rotatably mounted in said housing parallel to the first said shaft and movable longitudinally with respect thereto, a narrow faced gear secured to said second shaft and meshing with, and driving, the first gear, cooperating locking members on said narrow faced gear and in the housing adapted to lock the second shaft against rotation and thereby prevent rotation of the drum, means mounted on second shaft for forcing the locking members on the narrow faced gear and in the housing into locking association, and means for moving said shaft longitudinally to move said locking members out of locking association and thereafter rotate said second shaft to cause a rotation of the first shaft and winding drum in either direction.

In testimony whereof, I have signed my name to this specification.

JAS. R. MACLEAR.
